PERCOLATOR BOILER

Allen P. Livar, Dayton, Ohio, assignor to Chrysler Corporation, Detroit, Mich., a corporation of Delaware

Application June 3, 1941, Serial No. 396,408

11 Claims. (Cl. 122—225)

My present invention relates to boilers of particular utility for house heating applications, and means whereby the boiler may be provided with domestic hot water heating means.

The primary object of the present invention is to provide a boiler having quick steaming or water heating ability, the present invention being capable of providing steam or hot water in materially shorter time from the inception of firing than any boiler heretofore known to me, whereby lagging of the house temperature below the setting of the house thermostat is materially reduced. With slow starting boilers the house thermostat is either set at an excessive temperature in order to reduce the extent and duration of cold periods, or the house is periodically too cold for comfort during the periods that the boiler is trying to reach a proper temperature. The present invention is designed to provide heat within a few minutes after the thermostat calls for heat so that the thermostat may be set at the most comfortable point and hot water or steam will nevertheless be supplied to the radiators before the house temperature has had a chance to fall below the comfort zone.

In connection with the foregoing the present invention is designed to supply steam for a steam heating system or hot water for a hot water heating system without change in the construction of the boiler, and the foregoing object of the present invention will be achieved in either type of system.

A secondary object of the present invention is to provide a sectional boiler having the least weight and size per unit of rating of any sectional boiler known to me. The foregoing characteristics are achieved in part by forming the sections with water legs, water bottoms, and water wall portions so as to utilize all available heat generated in the firing chamber, and in part by the arrangement of circulation inducing means further characterizing my invention.

The foregoing objects of my invention are principally achieved by providing a sectional boiler of which at least one section, the rearmost section when considering the front section as being that section through which fuel is delivered to the firing chamber, is a return or downflow section, and all other sections, whether such sections be one, two, or as many as six or seven in number, are riser or upflow sections. A feature of my invention is the provision of a water wall at the rear of the combustion chamber of cross-sectional area at least as large as the combined

cross-sectional areas of the water leg portions of the riser sections.

The objects and advantages of the foregoing are in part realized by forming each riser section with a crown wall overlying the heating chamber, and providing above said crown wall a pair of baffles located within the water space and one at each side of the vertical center line of the section, each of said baffles being closer to the vertical center line of the section at the upper extremity thereof than at the lower extremity thereof whereby said baffles form a Venturi throat collecting hot water and steam from above the crown wall and causing the same to travel upward centrally of the section at accelerated velocity. Hot water and steam are thus drawn rapidly from the most heated portions of the sections and caused to circulate rearwardly through connecting nipples at the tops of the section, downward through the water wall portion of the rear section, forwardly into the water leg portions of the riser sections and again into contact with the most heated portions above the firing chamber. By thus increasing the flow of water through the sections, I have greatly increased the heat transfer per pound of cast iron over any sectional boiler construction known to me.

The increased rate of circulation and the increased rate of heat transfer are achieved in part by providing a pair of parallel flue passages lying wholly within the water space of each section and one at each side of the section, said flue passages forming a throat of slightly wider width than the narrowest point of the Venturi throat formed by the baffles and extending above the baffles. The jet action of the steam and hot water emerging from the Venturi throat induces rapid circulation of water around the flue sections, upward from the sides of the sections adjacent the baffles and upward from the water leg portions of the sections, thus causing greater heat transfer from every portion of the sections and assuring high efficiency by removing all available heat from the flue gases before permitting the same to be exhausted.

As an aid to the foregoing I preferably provide a plurality of rows of staggered heat transfer pins, preferably cast integrally with the walls of the boiler sections, adjacent the area embraced by the baffles, and below the flue sections and above the crown wall, whereby a greatly increased rate of heat transfer at the portion of the section forming the inspirator is achieved. Preferably the pins are tapered and rectangular in cross section, the pins of each row overlying the spaces

between the pins of the row beneath in order that the flue gases may be caused to travel through a plurality of tortuous paths with excessive turbulence.

A further object of my invention is to provide means whereby the tremendously turbulent action in the outlet nipples of the sections caused by the geyser or fountain effect of the inspirator will not result in the entraining of water with the escaping steam when the boiler is used as a steam boiler. This is achieved by providing a horizontal baffle in the rear section whereby steam emerging from the forward or riser sections is caused to spread laterally toward the side walls of the last section before emerging into the pipe connection which is placed vertically above the horizontal baffle. Centrifugal action, therefore, assures the separation of water droplets from the steam, the collection of the same on the side walls of the last section, and the return of the water into the main body of water.

A further object of the present invention is to provide a boiler having the foregoing characteristics which may be readily adapted to have incorporated therewith a domestic water heater of the coil type, which heater may be of large capacity, simply manufactured and easily installed. The combination so achieved delivers a greater supply of suitably heated water within a lesser period of time than any comparable domestic hot water and boiler combination within my knowledge. This object is achieved by so forming the rearmost or downflow section as to be capable of receiving a heater coil arranged in the path of flow of the boiler water.

The objects and advantages of the present invention will be more readily understood by reference to the following specification taken in connection with the accompanying drawings wherein like numerals refer to like parts throughout.

In the drawings, Fig. 1 is a vertical central section taken along line 1—1 of Fig. 2, my present invention being illustrated as a three-section boiler comprising a rearmost or downflow section, an intermediate riser section, and a foremost riser section or fire-door section. It is to be appreciated that the number of intermediate riser sections may be increased according to the capacity desired. The boiler is illustrated when operating as a steam boiler, the normal water level and the approximate water level at the center line when percolating or geysering action is taking place being shown, but it is to be appreciated that the same boiler may be used as a water boiler without change. There is also indicated in skeleton outline an inner fire pot located within the combustion chamber and the inner extremity of the blast tube of a typical oil burner showing the boiler adapted for oil firing, but it is to be appreciated that the same boiler may be fired by other fuels such as gas without change other than as required for mounting the burner utilizing such fuel upon the fire door section;

Fig. 2 is a vertical section taken substantially through the lateral, central plane of the intermediate riser section as indicated at line 2—2 of Fig. 3;

Fig. 3 is a side view in elevation of the boiler showing the oil burner mounted in place, and showing a domestic water heater associated with the rearmost section;

Fig. 4 is a vertical section taken substantially along line 4—4 of Fig. 3 and showing details of the domestic water heater; and,

Fig. 5 is a vertical section taken substantially along line 5—5 of Fig. 3 and showing details of the steam separator.

The present invention comprises a plurality of cast sections, there being a front or fire door section 10, at least one intermediate riser section 11, and a rearmost or downflow section 12. The number of intermediate riser sections may be varied at will according to the capacity of the boiler desired, and preferably the front section is so formed as to be characterized as a riser section as well as the intermediate sections. Each riser section is formed with water leg portions 13 adapted to embrace the firing means so as to form the side walls of a firing chamber 14. The rearmost section is also formed with water leg portions 16, these portions, however, opening fully throughout their length into a rear water wall portion 17. The outer surfaces of all of the water legs extend vertically upward to form the side walls of the boiler and are joined by the top walls of the sections forming the top wall of the boiler. Each section is preferably provided with lower water floor portions 18 extending beneath the firing chamber so as to insulate the firing chamber from the floor and collect all available heat. The sides of the inner walls of the water leg portions extend upward to form parts of a pair of flue passages 19 arranged in parallel, one at each side of the boiler section and within the water space of the section, and the central portions of the inner wall of each water leg portion are arched inwardly and joined above the firing chamber to form a crown wall 20 forming the lower wall of the water space of each section.

Water is introduced to the boiler through a radiator return pipe 21 connected to either the right or left lower corner of the rearmost section as may be desired, the other corner being provided with a plug 22. From the return pipe the water may spread into the water legs and into the water floor portions 18 through connecting nipples 23 joining the sections. The cross-sectional area of the water wall portion 17 of the rearmost section is at least as large as and preferably larger than the combined cross-sectional area of all of the water leg portions 13 so that all the water travelling upward through the water leg portion may be returned through the one downflow section. In order that the water may return to the downflow section, all of the sections are connected at their upper extremities by outlet nipples 24 joining the sections together, the outlet nipples preferably lying almost entirely above the normal water line of a steam boiler, above the flue passages and centrally of the boiler sections. The cross-sectional area of each nipple is such as to accommodate all of the water which can possibly flow thereto from the water leg portions through the inspirator portions to be described. Circulation of water is, therefore, upwardly through the water leg portions of all riser sections, rearward through the outlet nipples 24, downward through the rearmost section and forward into the water legs through the inlet nipples 23.

The front section 10 is provided with a mounting plate 30 having an inspection opening 31 and means for mounting a burner apparatus whereby the front section becomes a fire door section

as illustrated. The burner apparatus may comprise an oil burner 32 firing into a fire pot located within the firing chamber 14, although other types of burners may be utilized as desired. All of the sections are preferably drawn together by tie bolts 33 and made air-tight by gaskets 34. The sections when so detachably joined provide for the travel of combustion gases from the firing chamber, between the reduced water space portions of the sections, provided by the crown walls 20 and the walls rising thereabove, and into the flue passages 19, the flue gases being ejected into a collector 35 having means to mount a flue pipe 36. Thus, all of the flue passages are in communication with each other, with the firing chamber 14 and with the flue pipe 36. The flue gas travel is vertically upward into the parallel flue passages 19 and horizontally outward with a minimum of restriction so that the boiler may be adapted for any type of firing without change, this being particularly important with respect to gas firing which requires natural draft burning.

Rapid circulation of water within the water space of each section is principally achieved by providing a pair of baffles 40 lying wholly within the water space and one at each side of the vertical center line of the section, the baffles terminating at their upper extremities slightly below and inside of the lower, inner corners of the flue passages 19 and at their lower extremities above the crown wall 20 so as to permit flow of only a restricted quantity of water across the crown wall for the rapid formation of steam. The baffles converge upwardly and are preferably curved along flow curve lines so as to form Venturi throats for the steam and hot water arising from the hottest portion of the crown walls 20 immediately above the flame in the firing chamber, the Venturi throats tending to cause greatly increased velocity over that which would normally be achieved by open, gravity circulation. The water in the water legs 13 is also heated by radiation from the fire pot or from the flame and is also greatly heated by flue gases arising between the water spaces from the firing chamber. This water may have considerable steam entrained with it and is also heated more than some other portions of the water in the boiler so that it is desirable to bring this water rapidly to the surface in order to increase the rate of heat transfer by bringing colder water into contact with the portions of the section receiving the greatest amount of direct heat. For this purpose the lower inner corners of the flue passages are so arranged with respect to the baffles 40 and the inner walls of the flue passages 19 are so formed and spaced as to provide, together with the baffles 40, an inspirator tending to draw water from the water space at the sides of the baffles 40. As a result of the inspirating effect so achieved hot water and steam geysers upward far above the normal water line when the boiler is used to provide steam and falls toward the sides of the sections above the flue passages 19. Some of this water rapidly circulates around the outside of the flue passages 19 to be again heated and inspirated upward. Another part of the water flows rearwardly through the outlet nipples 24 and into the central portion of the rearmost section 12 to be recirculated through the boiler as previously described.

In order to achieve the greatest heating effect and to assure firing efficiency each section is provided with a plurality of heat transfer pins

41 extending toward adjacent sections in the region of the water space bounded by the crown wall 20 and the lower sides of the flue passages 19, the heat transfer pins thus surrounding the area within which the baffles 40 lie. The pins are preferably rectangular in section with their greatest dimensions horizontal and are arranged in staggered rows so that the pins of one row overlie the spaces between the pins of the next lower row. The flue gases are thus caused to traverse a plurality of tortuous paths, with excessive turbulence causing even the upper surfaces of the pins to be wiped by hot gases. In this manner the production of steam and hot water is materially increased and the greatest amount of heat permissible in good firing practice is abstracted from the burning fuel.

When the boiler is used for steam production it is, of course, apparent that all of the water flowing through the outlet nipples 24 returns through the downflow portion 17 of the rearmost section 12 as indicated by the approximate water level shown in Fig. 1. However, the boiler may be used for water heating in which case no change is necessary other than to provide for completely filling the sections and connected pipes with water. In this case, water circulation from and to the riser sections follows two paths, the hottest water tending to rise into the outlet 30 from the rearmost section and the cooler water tending to flow downward through the downflow portion 17 of the rearmost section to be reheated.

In order to provide for periodic cleaning of the heat transfer pins 41 the sections may be provided at either side with means for supporting removable cleanout doors 42. Also, the rearmost section may be provided with a central blowout plug 43 for cleaning sediment from the boiler. One or more of the intermediate sections 40 may be provided with a threaded opening 44 for mounting a safety plug as required by certain building codes.

When the boiler is used as a steam boiler, means for separating entrained water from the steam comes into effect, the separating means being of such character that the boiler may be used as a water boiler without impairing its efficiency. The separating means comprises a horizontal baffle 50 extending between the front 50 and rear walls of the rearmost section at the level of the tops of the outlet nipples 24, the baffle extending beyond the outlet nipples 24 appreciably toward the side walls of the section. Steam and entrained water which emerge through the nipples from the riser sections strike the rear wall of the rear section so that some water tends to collect on the rear wall and run down into the water flowing into the downflow portion 17. The steam is then forced to turn and spread turbulently toward the side walls of the rearmost section 12, thus tending by combination of change of direction and centrifugal effect to throw the entrained water against the side walls where it collects and runs down the side walls. The further changes of direction upward and inward toward the central steam pipe connection 51 as shown in Fig. 5 assure complete separation of entrained water. When used as a water boiler the baffle 50 aids efficiency of the house heating radiators since it tends to permit only the hottest water to rise into the radiator system.

As seen in Fig. 1 the water wall portion 17 of the rearmost section is preferably formed in part by a removable plate 55 of considerable extent

mounted upon a flanged opening in the rear wall and suitably gasketed by gasket means 56. In order to provide for domestic hot water heating the plate 55 may be removed and a flanged shell 60 substituted therefor, the shell being of sufficient size to accommodate a portion of a tubular heat exchanger 61, part of which extends through the flanged opening into the direct path of the water flowing downward through the downflow portion 17. Thus, water flow is deflected into the shell to contact all of the heat exchanger, and the free cross-sectional area of the downflow portion is maintained at least as large as the combined water leg areas. The heat exchanger 61 may comprise two coils 62 and 63 suitably arranged to present the greatest amount of heat transfer surface within the limits desired, and suitably connected to an inlet header 64 and an outlet header 65. The coils may be arranged in series or in parallel as desired or as dictated by the hardness characteristics of the water, the rate of flow, and the temperature rise demanded by the particular installation. In either event it is preferred to have the inlet manifold at the bottom of the shell 60 so as to provide for counterflow of the water in the coil with respect to the downflow stream in the portion 17. The rapid circulation of heated water achieved by the inspirating or percolating effect of the riser sections assures faster supply of domestic hot water than any similar tankless heater-boiler combination of which I am aware.

Having illustrated and described a form of my invention it should be apparent to those skilled in the art that the same may assume modifications in arrangement and detail. All such modifications as come within the scope of the following claims are considered to be a part of my invention.

I claim:

1. A boiler comprising at least two cast sections, one of said sections constituting a riser section and another of said sections constituting a downflow section, said riser section being formed to provide a fire space having a crown wall, a water space above the crown wall of the fire space and parallel flue passages within the water space at each side of the section, and said downflow section being formed to provide a water space at the top thereof and parallel flue passages within the water space at each side of the section, said sections being detachably joined together with their flue passages in communication with each other and with said fire space, means connecting the water spaces of the sections centrally of the sections above said flue passages and other means connecting the water spaces of the sections below the crown wall of the fire space of said riser section, said riser section being provided with a pair of baffles located within the water space and one at each side of the vertical center line of the section, each of said baffles being closer to the vertical center line of the section at the upper extremity thereof than at the lower extremity thereof and each of said baffles terminating at its upper extremity in proximity to the adjacent flue passage and at its lower extremity in proximity to the crown wall of the fire space, said baffles providing a Venturi throat whereby steam and hot water from above the crown wall of the fire space are caused to travel upward between the flue passages at accelerated velocity, and said baffles and flue passages forming an inspirator whereby water from adjacent the flue passages and the

5 sides of the water space is caused to circulate upward between the flue passages and into the downflow section by the inspirating effect of the accelerated stream emerging from between said baffles.

2. A boiler comprising at least two cast sections, one of said sections constituting a riser section and another of said sections constituting a downflow section, said riser section being formed to provide a fire space having a crown wall, a water space above the crown wall of the fire space and parallel flue passages within the water space at each side of the section, and said downflow section being formed to provide a water space at the top thereof and parallel flue passages within the water space at each side of the section, said sections being detachably joined together with their flue passages in communication with each other and with said fire space, means connecting the water spaces of the sections centrally of the sections above said flue passages and other means connecting the water spaces of the sections below the crown wall of the fire space of said riser section, said riser section being provided with a pair of baffles located within the water space and one at each side of the vertical center line of the section, each of said baffles being closer to the vertical center line of the section at the upper extremity thereof than at the lower extremity thereof and each of said baffles terminating at its upper extremity in proximity to the adjacent flue passage and at its lower extremity in proximity to the crown wall of the fire space, said baffles providing a Venturi throat whereby steam and hot water from above the crown wall of the fire space are caused to travel upward between the flue passages at accelerated velocity, and said baffles and flue passages forming an inspirator whereby water from adjacent the flue passages and the sides of the water space is caused to circulate upward between the flue passages and into the downflow section by the inspirating effect to the accelerated stream emerging from between said baffles, said downflow section being provided with a steam outlet at its upper extremity whereby steam may be withdrawn from the boiler.

3. A boiler comprising a front section, a back section, and at least one intermediate section, said front section and intermediate section or sections constituting riser sections and said back section constituting a downflow section, each of said riser sections being formed to provide a fire space having a crown wall, a water space above the crown wall of the fire space and parallel flue passages within the water space, and said downflow section being formed to provide a water space at the top thereof and parallel flue passages within the water space at each side of the section, said sections being detachably joined with their fire spaces in communication to form a firing chamber and with the flue passages of each section in communication with each other and with said firing chamber, means connecting the water spaces of the sections centrally thereof above said flue passages and other means connecting the water spaces of the sections at a lower level, each of said riser sections being provided with a pair of baffles located within the water space and one at each side of the vertical center line of the section, each of said baffles being closer to the vertical center line of the section at the upper extremity thereof than at the lower extremity thereof and each of said baffles terminating at its upper extremity in proximity to the adjacent flue passage and at its lower extremity in proximity to the crown wall of the fire space, said baffles providing a Venturi throat whereby steam and hot water from above the crown wall of the fire space are caused to travel upward between the flue passages at accelerated velocity, and said baffles and flue passages forming an inspirator whereby water from adjacent the flue passages and the

adjacent flue passage and at its lower extremity in proximity to the crown wall of the fire space, said baffles providing a series of Venturi throats whereby steam and hot water from above the crown walls of the fire spaces are caused to travel upward between the flue passages at accelerated velocity, and said baffles and flue passages forming inspirators whereby water from adjacent the flue passages and the sides of the water spaces is caused to circulate upward between the flue passages and into the downflow section by the inspirating effect of the accelerated streams emerging from between said baffles.

4. A boiler comprising a front section, a back section, and at least one intermediate section, said front section and intermediate section or sections constituting riser sections and said back section constituting a downflow section, each of said riser sections being formed to provide a fire space having a crown wall, a water space above the crown wall of the fire space and parallel flue passages within the water space, and said downflow section being formed to provide a water space at the top thereof and parallel flue passages within the water space at each side of the section, said sections being detachably joined with their fire spaces in communication to form a firing chamber and with the flue passages of each section in communication with each other and with said firing chamber, means connecting the water spaces of the sections centrally thereof above said flue passages and other means connecting the water spaces of the sections at a lower level, each of said riser sections being provided with a pair of baffles located within the water space and one at each side of the vertical center line of the section, each of said baffles being closer to the vertical center line of the section at the upper extremity thereof than at the lower extremity thereof and each of said baffles terminating at its upper extremity in proximity to the adjacent flue passage and at its lower extremity in proximity to the crown wall of the fire space, said baffles providing a series of Venturi throats whereby steam and hot water from above the crown walls of the fire spaces are caused to travel upward between the flue passages at accelerated velocity, and said baffles and flue passages forming inspirators whereby water from adjacent the flue passages and the sides of the water spaces is caused to circulate upward between the flue passages and into the downflow section by the inspirating effect of the accelerated streams emerging from between said baffles, said downflow section being provided with a steam outlet at its upper extremity whereby steam may be withdrawn from the boiler.

5. A cast boiler section having substantially parallel front and rear walls, substantially parallel side walls forming with said front and rear walls the vertical walls of a water space, an outlet opening located at the top of said water space in at least one of said front and rear walls and midway between said side walls, a fire space crown wall forming the bottom of said water space, an inlet opening located in at least one of said front and rear walls and below said crown wall, and a pair of internal baffles located within said water space and one at each side of the vertical center line of the section, said baffles converging upwardly and terminating at their upper ends beneath said outlet opening and at their lower ends above said crown wall.

6. A cast boiler section having substantially parallel front and rear walls, substantially paral-

lel side walls forming with said front and rear walls the vertical walls of a water space, an outlet opening located at the top of said water space in at least one of said front and rear walls and midway between said side walls, a fire space crown wall forming the bottom of said water space, an inlet opening located in at least one of said front and rear walls and below said crown wall, a pair of internal baffles located within said water space and one at each side of the vertical center line of the section, said baffles converging upwardly and terminating at their upper ends beneath said outlet opening and at their lower ends above said crown wall, and a plurality of heat exchanger pins extending from at least one of said front and rear walls externally of said water space in the area surrounding the location of said baffles.

7. A cast boiler section having substantially parallel front and rear walls, substantially parallel side walls forming with said front and rear walls the vertical walls of a water space, an outlet opening located at the top of said water space in at least one of said front and rear walls and midway between said side walls, a fire space crown wall forming the bottom of said water space, an inlet opening located in at least one of said front and rear walls and below said crown wall, a pair of internal baffles located within said water space and one at each side of the vertical center line of the section, said baffles converging upwardly and terminating at their upper ends beneath said outlet opening and at their lower ends above said crown wall, and a plurality of heat exchanger pins extending from at least one of said front and rear walls externally of said water space in the area surrounding the location of said baffles.

8. A cast boiler section having substantially parallel front and rear walls, substantially parallel side walls forming with said front and rear walls the vertical walls of a water space, an outlet opening located at the top of said water space in at least one of said front and rear walls and midway between said side walls, a fire space crown wall forming the bottom of said water space, an inlet opening located in at least one of said front and rear walls and below said crown wall, a pair of internal baffles located within said water space and one at each side of the vertical center line of the section, said baffles converging upwardly and terminating at their upper ends beneath said outlet opening and at their lower ends above said crown wall, and a plurality of heat exchanger pins extending from at least one of said front and rear walls externally of said water space in the area surrounding the location of said baffles, said pins being arranged in a plurality of horizontal rows with the pins of each row overlying the spaces between the pins of the next lower row.

9. A cast boiler section having substantially parallel front and rear walls, substantially parallel side walls forming with said front and rear walls the vertical walls of a water space, an outlet opening located at the top of said water space in at least one of said front and rear walls and midway between said side walls, a fire space crown wall forming the bottom of said water space, an inlet opening located in at least one of said front and rear walls and below said crown wall, a pair of internal baffles located within said water space and one at each side of the vertical center line of the section, said baffles converging upwardly and terminating at their upper ends beneath said outlet opening and at their lower ends above said crown wall, and a plurality of heat exchanger pins extending from at least one of said front and rear walls externally of said water space in the area surrounding the location of said baffles, said pins being rectangular in section and staggered vertically whereby flue gases traversing at least one of said front and rear walls are caused to travel through a plurality of tortuous paths with excessive turbulence.

10. A boiler comprising a plurality of sections detachably joined together, a plurality of said sections having water legs unitedly forming the side walls of a firing space and the rearmost of said sections having a water wall portion forming the rear wall of said firing space, said water wall portion having a cross-sectional area at least as great as the combined cross-sectional area of all of said water legs, communicating outlet nipples joining the upper portions of all of said sections, communicating inlet nipples joining the lower portions of all of said water legs

and said water wall portion, and inspirator means above the water legs of each section other than said rearmost section, said inspirator means comprising upwardly converging baffles arranged to collect steam and hot water from above the firing space and direct the same toward said outlet nipples, whereby accelerated circulation from said water legs through said outlet nipples, downward through said water wall portion, and back into said water legs by way of said inlet nipples is created.

10. A boiler comprising a plurality of sections detachably joined together, a plurality of said sections having water legs unitedly forming the side walls of a firing space and the rearmost of said sections having a water wall portion forming the rear wall of said firing space, said water wall portion having a cross-sectional area at least as great as the combined cross-sectional area of all of said water legs, communicating outlet nipples joining the upper portions of all of said sections, communicating inlet nipples joining the lower portions of all of said water legs and said water wall portion, and inspirator means above the water legs of each section other than said rearmost section, said inspirator means being arranged to accelerate circulation of steam and hot water through said sections from said water legs, through said outlet nipples, into said water wall portion, and back into said water legs, and said inspirator means comprising a pair of

centrally located, upwardly converging baffles having the lower ends thereof adjacent the top of said firing space.

11. A boiler comprising a plurality of sections 5 detachably joined together, a plurality of said sections having water legs unitedly forming the side walls of a firing space and the rearmost of said sections having a water wall portion forming the rear wall of said firing space, said water 10 wall portion having a cross-sectional area at least as great as the combined cross-sectional area of all of said water legs, communicating outlet nipples joining the upper portions of all of said sections, communicating inlet nipples 15 joining the lower portions of all of said water legs and said water wall portion, inspirator means above the water legs of each section other than said rearmost section, said inspirator means being arranged to accelerate circulation of steam 20 and hot water through said sections from said water legs, through said outlet nipples, into said water wall portion, and back into said water legs, and said inspirator means comprising a pair of centrally located, upwardly converging baffles 25 having the lower ends thereof adjacent the top of said firing space, and means for causing rapid heat transfer through the walls of said sections adjacent said baffles comprising heat transfer pins extending laterally of the adjacent walls of said 30 sections.

ALLEN P. LIVAR.
